TO MARKEM MACHINE COMPANY, OF BOSTON, MASSACHUSETTS, A CORPORATION
OF MASSACHUSETTS.

TYPE CHASE.

Application filed March 13, 1924, Serial No. 698,869. Renewed April 10, 1928.

This invention relates to a type chase or type holder for holding type which is used in a printing machine or a marking machine and the object of the invention is to provide 5 an improved type chase which is constructed so that the type can be easily set up therein and can be given any desired spacing, both as to the spacing between the lines and the spacing of the words in the lines.

10 The type chase embodying our invention comprises a skeleton frame which is constructed to be secured in a printing machine or in the printing head of a marking machine and which is provided with one or more type-carrying bars extending longitudinally thereof, each bar being adapted to support the type forming a line. Adjustable longitudinally 15 of each bar are pairs of word gauges by which the position of the type forming the separate words are determined. These word gauges can be adjusted into any desired position along each bar thus providing for any desired spacing of the words.

20 In order to give an understanding of the invention we have illustrated in the drawings a selected embodiment thereof which will now be described after which the novel features 25 will be pointed out in the appended claims.

Fig. 1 is a plan view of a type chase embodying our invention;

30 Fig. 2 illustrates the printed impression which will be made by the type set up as indicated in Fig. 1;

Fig. 3 is a partial under side view of the 35 type chase;

Fig. 4 is a sectional view showing the type which is secured in the head of a printing machine, the section through the type chase being taken on the line 4—4, Fig. 1;

40 Fig. 5 is an enlarged section on the line 5—5, Fig. 1;

Fig. 6 is a perspective view of a type element;

45 Fig. 7 is a perspective view of a gauge used to position the type;

Fig. 8 is a perspective view of a clamping member by which each gauge is held in position.

50 The type chase comprises a skeleton frame 1 which is herein shown as formed with the two side members 2 which are connected by the end members 3, thus making a rectangular frame. This frame is designed to be se-

cured into the printing head of a printing or marking machine and for this purpose it may 55 have any desirable construction. Merely for the purpose of illustration we have shown in Fig. 4 a portion 4 of a printing head of a marking machine which is formed on one edge with a lip 5 and at the other edge is provided with a pivoted clamping member 6, the latter being pivoted to the head at 7. Where this kind of a printing head is employed one side member 2 of the frame 1 will be formed with a lip 8 to interlock with the lip 5 and the 60 other side will be formed with the lip 9 to be engaged by the pivoted clamping member 6. This construction is one which permits the frame to be readily removed from or replaced 65 in the printing head 4.

70 The frame 1 is provided with one or more type-carrying bars 10, there preferably being a plurality of such bars. Each bar is adapted to support a line of type and these type-carrying bars are adjustably mounted in the frame 1 so that they can be adjusted relative 75 to each other to provide any desired spacing between the lines.

78 In the construction herein shown each bar 10 is formed with a type-receiving slot 11 80 which extends longitudinally thereof and into which the type 32 are inserted.

85 While the slotted bar may be made in various ways without departing from the invention we have herein shown a construction 85 which comprises two metal strips 12 extending parallel to each other and forming between them the slot 11, said strips being connected together at their ends by filling blocks 13 to which the strips are secured. Each pair 90 of strips 12 and the blocks 13 at the ends thereof constitutes a type-carrying bar having a slot 11 extending longitudinally thereof.

95 The type which we propose to use with our type chase have the construction shown in Fig. 6, each type having the body portion of a size to be received in the slot 11 with the type character 14 at one end and with the other end enlarged to form the head 15, the latter presenting shoulders 16 which rest on 100 the strips 12. The type is set up in the type chase by merely dropping them into the slots 11 so that the shoulders 16 will rest on the strips 12.

105 The type-carrying bars are adjustably mounted in the frame so that they can be

- adjusted relative to each other thereby to vary the spacing of the lines and while this adjustment may be effected in various ways we regard the construction herein illustrated as a convenient and practical one. The end members 3 of the frame are formed with the flanges 16 which extend from one side piece to the other and each of which is provided with the slot 17. Each filling block 13 of the type-carrying bars is formed with a rib 18 fitting within the slot 17 as shown in Fig. 5. The type bars are, therefore, adjustable transversely of the frame and longitudinally of the slots 17.
- 10 Means are provided for clamping the type bars in adjusted position, such means being herein shown as a clamping block 19 which is associated with each spacing bar 13 and which is connected thereto by a clamping screw 20.
- 20 Each clamping block 19 is provided with a rib 33 which enters the slot 17, such rib preventing the clamping member from turning. When the clamping screws 20 are loosened slightly the type-carrying bars can be adjusted 25 in a transverse direction or in a direction longitudinally of the slots 17 and after they are properly spaced relative to each other they may be locked in adjusted position by the clamping screws 20.
- 30 Associated with each type-carrying bar 10 are a plurality of word gauges which are for the purpose of positioning the type for the individual words.
- 35 There are preferably two or a pair of word gauges for the type forming each word, the gauges of each pair forming a space between them in which the type for any word is placed. The gauges of each pair are indicated at 21, 22, the two gauges being similar to each other except that one is a "right" and the other a "left." Each gauge is in the nature of a block having the slots 23 to receive the strips 12 so that the gauges ride on and embrace the strips. The gauges are clamped in adjusted 40 position by means of clamping members 24 which are situated beneath the strips 12 and are also provided with slots or grooves 25 to receive the lower edges of the strips. The clamping members are connected to the blocks 45 by clamping screws 27.
- 50 From the above it will be seen that when the clamping screws are tightened the blocks are clamped to the strips and will be retained in adjusted position; while when the clamping screws are loosened the blocks may be adjusted longitudinally of the strips but cannot be dislodged. The grooves 25 in the clamping members serve to prevent the latter from turning when the clamping screw is tightened 55 or loosened.
- 60 These pair of word gauges 21, 22 will be adjusted on the type-carrying bars in the proper positions to receive the type for printing the desired words and when they are 65 properly adjusted the type can be simply

dropped into the slots of the type-carrying bars between the gauges of each pair. This greatly facilitates the setting up of the type.

The type chase has the further advantage that whenever it is desired to set up the type 70 therein to duplicate the printing on any label or the like, the frame may be placed over the label and the latter used as a templet for adjusting the type-carrying bars and the word gauges. For instance, in Fig. 2 is illustrated a label 26 which has four lines of printing, one line having the words "Brown" and "Oxford", the next line having the words "Size" and "6½", the third line having the words "Width" and "B" and the fourth line 75 having the words "Price" and "8.00". If it is desired to duplicate this printing the frame 1 will be placed over the label 26 as shown in Fig. 1 and the type-carrying bars 10 will be adjusted so that the printing on the label is 80 visible through the slots 11 of the bars as shown at the top of Fig. 1. When the type-carrying bars 10 are thus adjusted the clamping screws 20 are tightened to lock them in position. The pairs of word gauges 21, 22 85 are then adjusted longitudinally of the bars so that the gauges are located at the ends of each of the words as they are visible through the slots 11.

In Fig. 1, for instance, the upper type bar 90 has no type therein and the word gauges 21, 22 of the pairs are shown as being adjusted so that a word on the label is visible between the gauges of each pair. When the gauges have thus been adjusted the clamping screws 27 100 are tightened thus locking the gauges in place. After the word gauges have thus been adjusted then the type for printing the words may be dropped into the slots 11 between the word gauges, this completing the type setting operation.

In Fig. 1 the type are shown as in position in the lower three type-carrying bars and the printing on the label is indicated by the dotted lines. In the upper type-carrying bar, however, the type are not in position and the printing on the label is clearly visible.

It will thus be seen that with this construction the printed label can be readily used as a templet for setting type-carrying bars and the word gauges for receiving type to print a duplicate label.

We claim:

1. In a type chase, the combination with a skeleton frame, of a plurality of separately adjustable type-carrying bars carried thereby, each bar comprising two rigidly connected parallel strips forming between them a type-receiving slot open at both the top and bottom of the bar, type elements adapted to be inserted in said slots, each type element having positioning shoulders to rest on the upper edges of the strips and being of a length to project through the slot and below the bar, and word gauges adjustably carried 120

by the bars for determining the position of the type for printing any word.

2. In a type chase, the combination with a skeleton frame, of a plurality of separately adjustable type-carrying bars carried thereby, each bar comprising two rigidly connected parallel strips forming between them a type-receiving slot which is open at both sides of the bar, type elements adapted to be inserted in said slots, each type element having positioning shoulders to rest on the edges of the strips and being of a length to project through the slot and beyond the other side of the bar, and word gauges adjustably carried by the bars for determining the position of the type for printing any word, each word gauge having slots in its under face in which the strips are received, clamping members engaging the under side of the strips and clamping screws connecting the gauge members and clamping members.

3. In a type chase, the combination with

a skeleton frame, of a plurality of separately adjustable type-carrying bars carried thereby, each bar comprising two rigidly connected parallel strips forming a type-receiving slot between them, type elements adapted to be inserted in said slots, each having positioning shoulders to rest on the strips and being of a length to project through the slot and word gauges adjustably carried by the bars for determining the position of the type for printing any word, each word gauge having slots in its under face in which the strips are received, clamping members engaging the under side of the strips and clamping screws connecting the gauge members and clamping members, said clamping members having interlocking engagement with the strips.

In testimony whereof, we have signed our names to this specification.

CARL E. PUTNAM.
FRED A. PUTNAM.
